Primary Examiner — Daniel J Domino*Assistant Examiner* — Samina Vieth(74) *Attorney, Agent, or Firm* — Hayes Soloway PC(57) **CLAIM**

The ornamental design for a remote control, as shown and described.

DESCRIPTION

The patent or application file contains at least one drawing executed in color. Copies of this patent or patent application publication with color drawings will be provided by the Office upon request and payment of the necessary fee.

The FIGURE is a front view of parts of a remote control illustrating my new design.

The broken lines showing portions of the article form no part of the claimed design.
